ELECTRIC CIRCUIT INTERRUPTER

Hermann Burmeister, Berlin-Spandau, Germany,
assignor to General Electric Company, a corporation of New York

Application January 28, 1937, Serial No. 122,774
In Germany February 11, 1936

3 Claims. (Cl. 200—144)

This invention relates to electric circuit interrupters, more particularly to circuit interrupters of the air-break expulsion type wherein a gas formed by decomposition of a material by the arc 5 upon opening of the circuit is utilized to interrupt the arc.

In a well-known form of circuit interrupter of the aforesaid type, the arc is drawn in a narrow channel or tube composed of material which, 10 under the influence of the heat of the arc, emits gases or vapors tending to extinguish the arc. Inorganic materials, such as for example, boric acid, ammonium alum, etc., have been proposed as the gas-emitting material. In these substances 15 water is chemically combined so that under the influence of the arc vapors are released for the arc-extinguishing process. These vapors producing inorganic materials cannot, however, be molded or formed satisfactorily for circuit interrupting service since they lack the more desirable 20 mechanical characteristics such as strength and rigidity, which are necessary in connection with the explosive pressures developed during interruption of the circuit.

For these reasons, organic materials, such as 25 hard rubber, paper, or other fibrous materials, which under the influence of the arc, also evaporate so as to emit an arc-extinguishing gas and also serve as a deflecting insulating service, are preferable. Moreover, these organic or fibrous 30 materials have the advantage that they can easily be formed in tubular and other shapes and have inherently high mechanical strength.

There are, however, certain disadvantages in 35 the use of circuit interrupter tubes composed of organic materials since to a great extent decomposition by the heat of the arc results in a reduction to carbon. Since the carbon formation may result in a film of soot along the insulating surface of the circuit interrupter, the interrupting 40 process, particularly in the case of high voltages, may be accompanied by flashover by reason of the conducting path formed by the carbon.

In accordance with the present invention, organic 45 materials, such as linen, paper, wool, etc., can be used in combination with impregnating materials, such as fluid artificial resin. With a sufficient amount of impregnating material and penetration, preferably with an impregnation of 50 more than 100 per cent, the fibrous or carrying material can, in the present case, be enclosed or sealed by the impregnating material so that a soot formation is avoided.

My invention will be more fully set forth in 55 the following description referring to the accom-

panying drawing, and the features of novelty which characterize my invention will be pointed out with particularity in the claims annexed to and forming a part of this specification.

Referring to the drawing the single figure 5 thereof is an elevational view partly in section of an electric circuit breaker of the expulsion type to which the present invention is applicable.

There is shown merely by way of example an electric circuit interrupter, more particularly, a 10 circuit breaker having means, such as the stationary contact 1 and the movable rod contact 2, for opening the circuit so as to form an arc, and an insulating structure 3 forming an arc chamber for closely confining the arc between 15 the contacts. The insulating structure 3 consists of a tubular member closed at the fixed contact end and open at the other end for receiving the rod contact. Upon opening of the circuit separation of the contacts 1 and 2 causes 20 formation of an arc which decomposes some of the material of the arc chamber walls 3. The gas so formed is under considerable pressure by reason of the comparatively close fit of the rod contact 2 in the fiber tube 3 with the result that 25 when the rod leaves the tube a blast of gas is released as indicated for interrupting the arc.

In accordance with the present invention the fluid artificial resin, when used as a means of impregnation may consist of a carbamide (amino 30 plastic mass). In these materials nitrogen is chemically combined so that in the circuit interrupting process this gas is released by the arc. The carrier material on the other hand, in so far as it comes into contact with the arc burns practically without residue so that the operation of the circuit interrupter is not hindered by the soot formation.

It has also been found that a further increase in the interrupting effect and also a greater freedom in the selection of the carrier materials without taking into account their soot forming characteristics, can be obtained if an appreciable admixture of carbonate, preferably an ammonium carbonate is added to the impregnating material. 40 Apparently in the arc-extinguishing process, the carbonate acts as a carrier of oxygen which converts the carbon produced in the switch tube under the influence of the arc heat into carbon monoxide or carbon dioxide respectively.

Thus, on the one hand a very effective arc-interrupting gas, namely carbonic acid, is produced, and on the other hand a soot formation is avoided by the combination of the car- 50 55

bon with oxygen produced by dissociation of the carbonate by the arc.

In lieu of ammonium carbonate (NH_4CO_3), there can also be used some carbonates wherein the hydrogen of the ammonium is totally or partially replaced by aliphatic or aromatic compounds. For example, tetraethyl ammonium carbonate, $(\text{N}(\text{C}_2\text{H}_5)_4)_2\text{CO}_3$, can be used in place of the ammonium carbonate or ammonium b10 carbonate. The advantage of these salts lies in the larger quantity of gas that can be produced, and especially in the larger hydrogen content. In regard to the latter, the carbonates of monomethylamine are particularly outstanding.

The admixture, in accordance with the invention of a carbonate to organic materials serving as gas producing materials for arc interrupting tubes of the character above discussed 20 also makes possible the use of the good arc-extinguishing properties of hard rubber. Following this method, a material is produced which, surprisingly, does not tend toward soot formation even under comparatively long exposure to 25 arcing, and which has a greater arc-extinguishing effect.

As an example of an admixture to hard rubber, calcium bicarbonate, calcium carbonate or magnesium carbonate can be used. These materials 30 are suitably added to the rubber in the vulcanizing process as a filling material. Further examples of filling materials include other carbonates, such as marble dust or chalk. A satisfactory final product can be obtained by volumetric mixture of 50 per cent (caoutchouc+sulphur) and 50 per cent marble dust. If desired, boric acid can also be used in place of part of the filling material.

It should be understood that my invention is 40 not limited to specific details of construction and arrangement thereof herein illustrated, and that changes and modifications may occur to one skilled in the art without departing from the spirit of my invention.

45 What I claim as new and desire to secure by Letters Patent of the United States is:

1. An electric circuit interrupter comprising means for opening the circuit so as to form an arc, and an insulating structure disposed adjacent and in confining relation to said arc, said insulating structure comprising a mechanically strong organic material impregnated with an in-

organic material which upon decomposition by said arc yields an arc-interrupting gas.

2. An electric circuit interrupter comprising means for opening the circuit so as to form an arc, and an insulating structure disposed adjacent and in confining relation to said arc, said structure consisting of a mechanically strong organic material impregnated with a substantially equal or greater amount of an inorganic material which upon decomposition by said arc 10 yields an arc-interrupting gas including carbon dioxide.

3. An electric circuit interrupter comprising means for opening the circuit so as to form an arc, and an insulating structure disposed adjacent and in confining relation to said arc, said structure consisting of a mechanically strong organic carrier material impregnated with an inorganic material including a carbonate so that said structure when subjected to said arc yields 20 carbon dioxide gas for interrupting said arc.

4. An electric circuit interrupter comprising means for opening the circuit so as to form an arc, and an insulating structure disposed adjacent and in confining relation to said arc, said structure consisting of a mechanically strong fibrous material impregnated with ammonium bicarbonate.

5. An electric circuit interrupter comprising means for opening the circuit so as to form an arc, and an insulating structure disposed adjacent and in confining relation to said arc, said structure consisting of an organic fibrous material impregnated with a carbonate in which hydrogen of an ammonium radical in chemical combination therewith is replaced wholly or partly by an organic compound.

6. An electric circuit interrupter including an arc-confining structure, said structure consisting of hard rubber impregnated with a carbonate 40 adapted to be decomposed by the heat of the arc for yielding an arc-extinguishing gas.

7. An electric circuit interrupter including an arc-confining structure, said structure consisting of hard rubber impregnated with calcium carbonate in approximately equal quantities by volume.

8. An electric circuit interrupter including an arc-confining structure, said structure consisting of an approximately equal mixture by volume 50 of hard rubber and marble dust.

HERMANN BURMEISTER.
